RECEPTACLE CLOSURE

Leslie R. N. Carvalho, Toledo, Ohio, assignor to
 Owens-Illinois Glass Company, a corporation
 of Ohio

Application April 24, 1937, Serial No. 138,704

3 Claims. (Cl. 215—38)

The present invention relates to improvements in receptacle closures and methods of forming and applying the same.

The principal object of the invention is to provide an improved form of air tight closure for liquor bottles and other containers which will operate effectively both as a primary seal and a temporary reseal and which may readily be removed from the container by the simple expedient of manually applying upward pressure to one side of the closure.

A still further object of the invention is to provide a closure having a resilient one-piece liner for the entire inner surface of the closure, which liner is maintained therein by an internal bead formed at the lower edge of the skirt or attaching flange, the bead having a three-fold function; first, to firmly grip and thereby retain the liner in position; second, to reinforce and stiffen or lend rigidity to the skirt; and third, to distort the medial portions of the liner skirt to thereby create an annular internal bead designed for holding engagement with a projection on the container.

It is a still further object of the invention to provide a resilient liner for closures of the type set forth above, which, unlike other liners that must be deformed to assume a cup-shape, thereby losing resiliency, is formed from a single flat blank that may, in the assembly process of the closure, be readily bent into the desired shape.

Yet another object of the invention is to provide a closure of the type set forth above which readily adapts itself to mass production by a machine process wherein the attaching skirt is in part rolled inwardly during application of the closure to a bottle, thus causing an annular area of the apron of the cup-shaped liner to be forced or bulged inwardly under a bead formed on the "finish" or top surface of the bottle neck, the bulge causing the closure and liner to be pulled downwardly onto the bottle to effect a top and side seal with the bottle finish in which no metal whatsoever touches the bottle finish while at the same time no part of the liner is exposed to view.

Other objects and advantages of the invention will become apparent hereinafter.

In the accompanying drawing:

Fig. 1 is a vertical sectional view taken through the preferred form of my improved closure showing the same applied to a container;

Fig. 2 is a vertical sectional view taken through the closure prior to application to a container;

Fig. 3 is a fragmentary perspective view, partly in section, of the skirt or attaching flange which forms a part of the closure illustrated in Fig. 1 or 2;

Fig. 4 is a vertical sectional view illustrating the three parts which cooperate to make up the

closure just prior to the final assembly operation and illustrating one step in the method of forming the closure;

Fig. 5 is a plan view of the blank from which the resilient liner is formed;

Fig. 6 is a view illustrating the preferred manner in which the closure may be removed from a container;

Fig. 7 is a sectional view of another form of my invention in which the liner shown in Fig. 5 is fitted into a one-piece skirted closure of more or less conventional design;

Fig. 8 is a sectional view of another form of my invention;

Fig. 9 is a sectional view of still another form of my invention.

The completely assembled closure (Figs. 1, 2 and 6) consists of a top portion 10, depending attaching skirt 12 or flange and a liner 14. The top portion 10 or button which, may be circular or polygonal in form, has its periphery rolled downwardly and inwardly to form a hollow bead 11 for attachment to the upper edge of a depending attaching skirt 12 or flange. The lower edge of the skirt 12 is turned inwardly and upwardly to form a hollow internal bead 13 which grips and compresses the lower edge of a cup-shaped resilient liner 14. The liner 14 is nested within the cap with the head portion 15 thereof in close engagement with the top portion 10 and with the skirt portion 16 thereof in close contact with the skirt 12. The medial regions of the skirt portion 16 of the liner 14 are bulged inwardly to provide an internal bead 17 with the result that the normal diameter across the medial regions of the liner skirt 16 is slightly less than the diameter of the bead 13 of the skirt 12 and the bead 18 on the container neck. Thus when the closure is telescoped over the finish of a bottle as shown in Fig. 1, the external bead 18 at the top end of the bottle neck 19, is engaged by the sides of the liner and the closure is frictionally held in position on the bottle neck. The tendency of the internal bead 17 on the liner is to seek a position below and in positive holding engagement with the bead 18 of the bottle neck thus drawing the closure downwardly onto the bottle and providing an effective top and side seal.

In Fig. 1 the closure is shown attached to a container in a fashion which will be practised at a distillery, for example. The medial region of the skirt 12 is rolled inwardly to form an annular bead 20 which, being disposed in alignment with the bead 17 on the liner and immediately below the bead 18 on the bottle neck, forces the bead on the liner into firmer holding engagement with the container neck, and creates a more positive inward bulge 17 in the medial regions of the skirt portion 16 of the liner. More

- over, an exceptionally effective seal is obtained between the bead 18 on the neck and the inwardly bulged or bowed portion of the liner. Consequently the pressure required to remove the closure from the bottle neck 19 or to replace the same is slightly greater than if the bead 20 were not formed in the skirt. For this reason the closure is well adapted for use as a primary seal as well as a "reseal."
- 10 The manner of removal of the closure from the bottle and the manner in which it may be replaced is obvious from an inspection of Fig. 6. The user merely tips or tilts the closure by exerting a manual upward push on one edge of
- 15 20 25 30 35 40 45 50 55 60 65 70
- Referring now to Figs. 3, 4 and 5, the individual parts of the closure are shown prior to their assembly. The metal portion of the closure which ultimately forms the attaching skirt 12 of the closure, is shown in the form of a continuous one-piece band 21 formed with the internal hollow bead 13 at its lower margin. Obviously this band could be formed from a strip having its ends united in any conventional manner as for example by a side seam. The upper edge of the band 21 is provided with an out-turned flange 24.
- The top portion 10 or "button" is the form of a shallow inverted cup-like member including a depending marginal flange 26.
- 30 The cup-shaped resilient liner 14 is formed from a flat blank 27 including the substantially circular central top portion 15 from which extend radially, an annular series of finger-like portions 29 that are designed to be bent at right angles to the blank in forming the skirt portion 16 of the liner. If preferred score lines 30 may be provided in the blank to define a line of boundary between the head portion 15 of the liner and the skirt portion 16 thereof.
- 40 In assembling the individual parts of the closure just described, the liner blank 27 is bent into the ultimate shape which it assumes in the completed closure. The skirt portion 16 of the liner is inserted into the band 21 so that the lower circular edge thereof extends into the hollow bead 13 while the head portion 15 of the liner closes the upper end of this band. The top portion 10 is then telescoped over the upper end of the band 21 in such a manner that the flange 26 thereof overlies the outwardly turned flange 24 on said band 21 (Fig. 4). The flanges 26 and 24 are then rolled over and locked together and at the same time the bead 13 at the lower edge of the band 21 is collapsed to firmly grip the lower edge of the liner 14, and thereby lock the liner in its nested position within the closure.
- In another form of the invention, the liner 14 (Fig. 7) is secured within a one-piece drawn metal shell 31 and held assembled therewith by an internal bead 32 at the lower margin of the attaching skirt or flange.
- In Fig. 8 I have illustrated a form of my closure formed from a single sheet of metal which is stamped and shaped to produce a shell having a radial "pry off" ledge 33 or head at the juncture of the top portion 34 and skirt 35. As indicated by the dotted and full lines, the bead 33 is reduced vertically in cross section after the liner 36 has been inserted in the closure. Consequently the liner is placed under compression in the skirt portions thereof and is bulged in-

wardly by virtue of this compression and also by virtue of the inwardly turned bead 37 (Fig. 9) provided on the lower edge of the skirt portion 35 of the shell which compresses the material of the liner in the vicinity of the free edge thereof.

In Fig. 9 the closure of Fig. 8 is provided with an inwardly directed annular bead 38 in the skirt portion of the shell which serves to reinforce the inwardly bulged portion of the liner and accentuate the bulge.

Various modifications of the invention may be resorted to without departing from the spirit thereof. For example, while the blank from which the resilient liner is formed, is shown as 15 having six radial portions 29 extending outwardly from the circular central portion 28, it is obvious that any number of such radial portions may be employed if desired. Furthermore, the method of assembling the various parts of the 20 closure may be altered without destroying the ultimate result. For example, while in the method of assembly described, the resilient liner is first inserted within the shell 21 and thereafter the top portion 25 is applied, the invention contemplates the assembling of the two metal parts of the closure first and finally inserting the resilient liner into the closure through the open lower end thereof.

I claim:

1. A sheet metal closure comprising a circular top portion, a depending skirt at the margin of the top portion, a liner including an annular portion coextensive with the interior width of the skirt, said skirt having an annular internal bead 35 and an inturned upwardly directed flange, said bead and flange cooperating with each other in securing the liner in the closure and effecting an inward bulging of a medial portion thereof while maintaining the liner and skirt in substantial intimate contact with each other throughout.

2. A sheet metal closure for receptacles comprising a cup-like shell, a resilient cup-like liner nested within the shell and in substantial coextensive intimate contact with the interior of the latter, an inwardly turned bead on the shell extending over and gripping the resilient material in the vicinity of the free edge of said liner and compressing and displacing the same to form an inwardly extending annular holding bead as an integral part of the liner, and an annular internal bead on the shell pressing inwardly on the resilient material in the vicinity of the holding bead to reinforce the same.

3. A closure for bottle necks having an external annular bead formed thereon comprising a shell having a circular top portion and a depending annular flange, a resilient liner nested within the shell in substantially coextensive contact with the interior thereof, an inwardly turned bead on said shell extending over and compressing the resilient material in the vicinity of the rim of said liner and displacing a portion of the material inwardly against the bottle neck below the bead thereof, and an internal annular bead formed medially on said annular flange bearing against the displaced portion of the liner and accentuating its displacement.
